UNITED STATES PATENT OFFICE.

MILTON LEVIN, OF NEW YORK, N. Y., ASSIGNOR TO LION SAFETY PIN CLUTCH COMPANY, INC., OF NEW YORK, N. Y., A CORPORATION OF NEW YORK.

FINGER-RING GUARD.

1,217,097.

Specification of Letters Patent. Patented Feb. 20, 1917.

Application filed November 26, 1912. Serial No. 733,630.

To all whom it may concern:

Be it known that I, MILTON LEVIN, a citizen of the United States, and resident of New York, in the county of New York and State of New York, have invented certain new and useful Improvements in Finger-Ring Guards, of which the following is a specification.

This invention relates to holding devices for finger rings and consists of a small spring that is easily attached to and detached from a ring as will be explained, reference being had to the following specification and claim and the drawing in which—

Figure 1 is a perspective view of the holding device to be applied to a ring.

Fig. 2 is a plan view of the holding device.

Fig. 3 is a perspective view of the device attached to a ring.

Fig. 4 is a section on line 4—4 of Fig. 3.

Referring to the drawing there is shown an endless wire bent with the two portions A and B parallel, and preferably forming an arc of larger diameter than that of the ring to which it is to be applied. The device is readily applied by means of a pair of pliers. The ends C and D fitting around the ring E and the intermediate portion A and B being contracted, whereby the holding device is kept securely in position.

When this holding device has been applied to a ring large enough to readily pass

over enlarged knuckles, such a ring will hold its position so that the seal, plate jewel or other projection will remain in the upper position. If the device is applied to a ring for a finger that tapers uniformly, it has the advantage that with very little pressure, the projecting part of the ring will retain its upper position with very slight pressure on the finger.

On account of the fact that the holding device is made in one piece of an endless wire with no projecting points, there is nothing that will cause it to be caught in fabric or to scratch objects with which it may come in contact.

The device is made of springy wire, preferably gold so as to hold the ring in position under slight but sufficient spring pressure.

What I claim as new is:

A finger ring guard consisting of an endless spring wire with parallel branches bent so as to form a curve, the convex portion of which is adapted to face the lower portion of the ring when the guard is attached thereto.

Signed at New York, in the county of New York and State of New York this 22nd day of Nov. A. D. 1912.

MILTON LEVIN.
